UNITED STATES PATENT OFFICE

2,655,653

CABLE PULLING MACHINE

Wilbord A. Chauvin, Albuquerque, N. Mex.

Application March 22, 1951, Serial No. 217,033

7 Claims. (Cl. 254—134.3)

1

This invention relates to new and useful improvements in cable pulling machines and the primary object of the present invention is to provide an apparatus for use in installing electrical conductors in conduits, especially in the sizes that exceed the normal strength of a mechanic's pull and the inertia that comes from irregular pull.

Another important object of the present invention is to provide a portable power winch for the pulling in or out of electrical wires or cables into conduits, and a winch which can be adapted to other limited uses, such as raising or lowering motors, switch gear and the like.

Yet another object of the present invention is to provide a machine of the aforementioned character that may be readily transported within a building to the desired location where the pulling in is to be done, and then quickly set to the proper angle and anchored in place for a pull at any angle.

A further object of the present invention is to provide a cable pulling machine including a winch that can be free spooled for pulling wire rope into conduits and a control for the winch whereby the winding and unwinding speed of the winch may be regulated in accordance with the size wires or cables commonly used in electrical installations.

A still further aim of the present invention is to provide a cable pulling machine that is simple and practical in construction, strong and reliable in use, efficient in operation and which is readily movable within a building or exteriorly of buildings by attachment to a towing vehicle.

Other objects and advantages reside in the details of construction and operation as more fully hereinafter described and claimed, reference being had to the accompanying drawings forming part hereof, wherein like numerals refer to like parts throughout, and in which:

Figure 1 is a diagrammatic view showing the present invention in use;

Figure 2 is a perspective view of the present invention with its cover applied;

Figure 3 is a top plan view of the present invention, the cover removed;

Figure 4 is a side elevational view of Figure 3;

Figure 5 is a side elevational view taken on the opposite side from Figure 4;

Figure 6 is a rear end view of the invention;

Figure 7 is a front end view of the invention; and,

Figure 8 is an enlarged detail view of the winch used in the present invention and showing the brake means therefor.

Referring now to the drawings in detail, wherein for the purpose of illustration, there is disclosed a preferred embodiment of the present invention, the numeral 10 represents a wheeled frame or welded steel trailer assembly whose rear

2

end supports pairs of legs 12 carrying axles 14 on which rubber tired wheels 16 are mounted.

A winch or cable drum 18 is supported for rotation in brackets 20 mounted on a platform 22. The platform 22 is fixed by welding or the like to the frame 10 and the winch 18 is disposed transversely of the frame intermediate the ends of the frame.

A pair of upper and lower guide pulleys 24 and 26 are mounted on a bracket 28 rising from the forward inwardly tapered end of the frame 10 and receive therebetween a cable or wire rope C extending forwardly from the cable drum or winch 18.

Means is provided for guiding cable being applied to or removed from the drum 18 and this means consists of a vertically swingable lever 30 pivoted to the platform for movement alongside of and in front of the cable drum 18. The lever 30 is formed with an intermediate looped portion 32 that opposes the drum 18 and which portion 32 slidably receives the cable C.

A power plant or motor 34 is supported on the platform 22 at the rear end of the frame and includes a drive shaft 36 on which a series of various sized sprockets 38 are mounted. The shaft 36 parallels the drum driving shaft 40 on which a series of various sized sprockets 42 are mounted. The sprockets 38 are arranged in pairs with the sprockets 42 with the sprockets of each pair of different size to permit a sprocket chain 44 to be trained about a selected pair of sprockets for driving the shaft 40 at a predetermined speed. A wire cage 46 is secured to the platform and encloses the sprockets 38, 42.

The forward portion of the platform 22 supports a depending tool chest 48 whose interior is accessible through an opening in the platform that is normally closed by a closure 50. The closure 50 is located between pairs of side supports 52 and 54 that rotatably support spools or drums 56 and 58 about which are wound electrical wires 60 for a purpose later to be described.

A pair of internally threaded vertical sleeves 62 is fixed by welding or the like to the forward end of the frame and one of these sleeves receivably engages a jack screw 64 having a lower smooth cylindrical end 66. A pressure foot 68 is threaded on the screw 64 and constitutes an anchoring means for guy wires or the like when the machine is anchored in a desired position.

The trailer 10 is of such a size as to permit the same to be manually pulled through doorways, however, a hitch 70 is mounted at the forward end of the frame to permit the frame to be readily attached to a towing vehicle so that the machine may be moved from one location to another in a convenient manner.

The power plant 34 is preferably of the electric type and includes a power box 72 and a control switch 74. A conductor 76 extends outwardly

from the box 72 and is adapted to be electrically coupled to the wires 60 when the machine is located relatively far from an outlet box or source of current.

A cover 78 is provided for the frame 10 and houses the power plant, the winch, the transmission gearing or sprockets and the reels or spools. The cover is suitably locked, as at 80, to the frame to prevent unauthorized use of the machine.

The winch supports an internally toothed ring gear 82 that meshes with a pinion carried by a stub shaft 84. The stub shaft 84 is rotatably supported by a side member 86 and supports a brake drum 88 and another pinion or small gear 90 that meshes with a large gear 92. The gear 92 is driven by a pinion 94 on the shaft 40.

The drum 88 is embraced by a brake band 96, one end of which is adjustably secured to the member 86 and the other end of which is attached to an operating lever 98 that is pivoted to the member 86. The lever 98 is urged to a brake releasing position by a spring 100. As the lever 98 is manually urged in one direction, the band 96 will be tightened about the drum 88 to reduce the speed the drum 88 is rotating.

The drum 88 supports a ratchet 102 for engagement by a pivotal pawl 104 to lock the shaft 84 against back rotation.

The supporting shaft 105 for member 82 is 30 slidably and rotatably received in a bearing 106 mounted on side member 86. The shaft 105 is formed with a pair of longitudinally spaced grooves in its outer periphery for selectively registering with a slot in the bearing 106 and these 35 grooves are so arranged that when one groove is in registry with the slot the teeth 92 and 94 are engaged whereas when the other groove is in registry with the slot, the teeth 92 and 94 are disengaged.

Means is provided for selectively retaining the teeth 92 and 94 engaged and disengaged. This means consists of a bar 108 that extends transversely across the bearing 106 and which enters the slot in bearing 106 and one of the grooves in shaft 105. The ends of a spring 110 are secured to the ends of bar 108 and the spring 110 surrounds the bearing 106 to hold bar 108 in the slot and a selected groove.

Having described the invention, what is claimed as new is:

1. A cable pulling machine comprising a wheeled frame, a platform mounted on the frame, a cable drum supported on the platform for rotation, a power means mounted on the platform, a drive connection between said cable drum and said power means, guide means on the platform and swingable back and forth along side of the cable drum for guiding cable being applied to or removed from the cable drum, vertically adjustable jack means carried by the frame for selectively retaining the frame horizontal and in a vertically inclined position, and means adjustably mounted on the jack means forming anchoring means for guy wires, whereby the frame may be retained anchored in a desired position.

2. The combination of claim 1 and a tool chest secured to and depending from the platform, said platform having an opening for access into the tool chest, and a closure hinged to said platform for closing the opening therein.

3. A cable pulling machine comprising an elongated frame including pairs of legs at one of its ends, axles carried by said legs and wheels on said axles, a jack means at the other end of said

frame for selectively raising and lowering the frame about the wheels as a fulcrum, anchor means for guy wires adjustable on the jack means whereby guy wires may anchor the frame in a desired position, a platform on the frame, a cable drum disposed transversely of the frame intermediate the ends of the frame and supported on the platform for rotation, power means on the platform and operatively connected to said drum, and a brake mechanism connected to the drum.

4. A cable pulling machine comprising an elongated frame including pairs of legs at one of its ends, axles carried by said legs and wheels on said axles, a jack means at the other end of said frame for selectively raising and lowering the frame about the wheels as a fulcrum, anchor means for guy wires adjustable on the jack means whereby guy wires may anchor the frame in a desired position, a platform on the frame, a cable drum disposed transversely of the frame intermediate the ends of the frame and supported on the platform for rotation, power means on the platform and operatively connected to said drum, guide rollers on the end of said frame that supports said jack means, guide means on said platform for guiding cable being applied to or removed from the drum, and a brake mechanism operatively connected to said drum.

5. A portable cable pulling machine comprising an elongated wheeled frame of such a width as to permit the same to pass through doorways, said frame including a forward end and a rear end, said rear end supporting the wheels of the frame, jack means at the forward end of the frame, a hitch also at the forward end of the frame, a platform on the frame, a cable drum rotatably supported on the platform, a motor mounted on the platform, an adjustable drive connection between said cable drum and said motor to vary the speed at which the drum is rotated and including a driven gear and a ring gear movable into and out of mesh with the driven gear and latch means selectively locking the ring gear in and out of mesh with the driven gear, a brake mechanism operatively connected to the drum, and guide means on the platform for cable being applied to or removed from the drum.

6. The combination of claim 5 wherein said drive connection includes a pair of spaced parallel shafts, a series of various sized sprockets on each shaft, and an endless sprocket chain embracing a selected sprocket on each shaft, one of said shafts being connected to the drum and the other of said shafts constituting the drive shaft of the motor.

7. The combination of claim 5 wherein said brake mechanism includes a brake drum, a brake band embracing said brake drum, and a spring urged, manually actuated lever connected to said band for tightening the band about the brake drum.

WILBROD A. CHAUVIN.
